COMB

Harry L. Athens and Otto W. Risto,
Valparaiso, Ind.

Application June 22, 1953, Serial No. 25,586

Term of patent 14 years

(Cl. D86—8)

To all whom it may concern:

Be it known that we, Harry L. Athens and Otto W. Risto, citizens of the United States, residing at Valparaiso, State of Indiana, have invented a new, original, and ornamental Design for a Comb, of which the following is a specification, reference being had to the accompanying drawing, forming a part hereof.

Fig. 1 is a side elevational view of a comb showing our new design;

Fig. 2 is a top plan view thereof;

Figs. 3 and 4 are sectional views on lines 3—3 and 4—4, respectively, thereof.

The side opposite that shown in Fig. 1 is identical to the side shown.

We claim:

The ornamental design for a comb, as shown and described.

HARRY L. ATHENS.
OTTO W. RISTO.
